CHANGEABLE SIGN

Stanley J. Cygan, Chicago, Ill., assignor to Poster Products, Inc., Chicago, Ill., a corporation of Illinois

Application October 31, 1956, Serial No. 619,426

2 Claims. (Cl. 40—142)

This invention relates to a changeable sign of the type wherein letters or other characters are removably mounted on a signboard.

The invention has for an important object the provision of a lightweight changeable sign which is very attractive while being durable and versatile yet economical.

A particular object is to provide a changeable sign entirely constructed of attractive, economical and lightweight plastic materials, which has diverse applications and is especially suited for use in retail establishments while maintaining the decor.

Another object is to provide a sign which may readily be mounted in various locations or moved from place to place, due to its compact and light construction, and on which the letters or other characters may be changed at will.

An additional object is to provide characters changeably mountable on a signboard which are light, attractive and durable yet economical, and which may be mounted and removed over and over without damaging them and yet which may be discarded if desired, due to their inexpensive nature.

A further object is to provide a signboard and characters each constructed of a single sheet of thermoplastic material, desirably molding each from a flat sheet.

Another object is to provide a sign construction wherein removable characters may be mounted simply by pressing them on the board, and removed simply by pulling them away from the board. The characters are also advantageously constructed so that they are stretchable, and mounting may be assisted by stretching the characters slightly.

A further object is to provide a sign wherein the surface constitutes a plurality of strips alternating with a plurality of channels or slots, and a selected number of channels at predetermined spacings are recessed or undercut for engaging the characters, with the surface of the board marked for identifying the channels having recessed sides.

An additional object is to provide a sign wherein characters of different sizes may be mounted rapidly and accurately, particularly small letters and dots, dashes and similar indicia.

These and other objects of the invention will be apparent on reference to the specification and to the attached drawings, in which like parts are identified by like reference symbols in each of the views, and in which:

Figure 1 is an elevational and schematic view of a preferred embodiment of the changeable sign, illustrating the arrangements for mounting indicia of different sizes and in varying locations;

Figure 2 is an enlarged back or bottom perspective view of the letter "o" as provided in a preferred form of the invention;

Figure 3 is an enlarged partial vertical sectional view illustrating a double-face embodiment of the sign, showing the letter "o" and a dash mounted on the opposite sides thereof; and

2

Figure 4 is a partial sectional view corresponding to Figure 3 and further enlarged to illustrate the construction for mounting the letters or characters on the signboard.

5 The invention resides in a particular combination and arrangement of parts which provide a number of advantages. A lightweight changeable sign is provided which is constructed of a thermoplastic sheet in the form of a signboard, and thermoplastic sheet material in the form of characters. The characters include integral flanges for removable mounting on the signboard.

The signboard includes a plurality of spaced parallel elongated strip portions comprising the surface of the sheet, and a corresponding plurality of spaced depending 15 parallel elongated channel portions formed in the sheet and alternating with the strip portions. The signboard thus presents a very pleasing appearance, due to a number of parallel surface strips and relatively narrow channels with all visible surfaces being uniformly attractive 20 plastic material.

The characters mountable on the signboard may be letters of the alphabet, numerals, or other indicia or may represent articles or may be pictorial in nature. They 25 constitute flexible resilient thermoplastic sheet material formed into three-dimensional characters having dependent integral flanges bent toward each other for engagement in the channels or slots of the signboard and for being retained thereon by the resiliency of the characters.

30 Referring to the drawings, a preferred embodiment of the changeable sign is illustrated in Figure 1 and generally indicated by the numeral 1. The sign includes a signboard 2 which is continuous and constitutes sheet material having a plurality of spaced parallel elongated strip portions 3 of equal width formed therein. A corresponding plurality of spaced depending parallel elongated channel portions 4 are formed in the unitary sheet or signboard 2. These channel portions are relatively narrow as compared to the strip portions 3, their widths being equal at the mouths thereof and being about one-fourth of the width of the strip portions. The sheet 2 may be mounted on a base 5 of any suitable material, such as wood or metal, for assisting in mounting the sign 1 in various locations. The sign is especially adapted for mounting wherever desired, such as on a wall, over a partition wall, on or extending from a post or column, hanging back to back in aisles, and in other convenient locations.

50 The narrow strip portions 3 have flat outer or upper surfaces and together form the flat outer surface 6 of the signboard 2. It is this surface upon which the characters, such as the letters of the alphabet illustrated, are mounted, with the bases or backs 7 of the characters (see Figure 4) resting thereon.

55 Of the channels 4, a number are substantially U-shaped, and a selected number at predetermined spacings or locations have a side which is recessed or undercut with respect to the integral strip portion 3 from which it depends. Thus, as illustrated especially in Figure 4, one of the channels 4 has a sloping or inclined side 8 which forms an acute angle α with the plane of the surface 6 of the signboard. This construction serves for mounting the characters, as will appear. In the illustrative embodiment, eight channels 4, identified by the letters A through H, each have one recessed side. In order to mount the 60 characters so that they are maintained on the signboard 2 by the resiliency of the characters, the recessed sides are inclined in opposite directions on each side of the center of the signboard 2, the center being between the channels E and F. In both cases, the inclination is towards the center of the signboard. An exception is the channel C for engaging the lower flange of the dot. The essential 70

requirement is that for each character, at least two sides which are recessed towards each other be provided in different channels 4 for engaging a pair of opposed flanges on the character.

The embodiment of Figure 1 is single-faced, having one signboard 2, and is constructed for mounting the base 5 against a wall or other surface. Figure 3 illustrates a double-faced construction, wherein two signboards are mounted back to back on an interposed support 9, which is preferably thin and lightweight, such as fiber or composition board, or plywood, or may be a wood frame.

Illustrative reference characters are represented in Figure 1 as mounted on the signboard support 2. To further illustrate the construction and mounting, Figure 2 shows the lower case letter "o," identified by the numeral 10, and Figure 3 shows the letter "o" and a dash, identified by the numeral 11, mounted on opposite faces of the sign. Figure 4 gives further details of the construction, showing a portion of the letter "o." The characters each constitute thermoplastic sheet material formed into three-dimensional characters having a pair of depending integral flanges 12. The flanges are continuations of opposite sides or ends 13 of the characters, and they are bent towards each other for engagement in a pair of channel portions 4 which have a recessed side 8. The raised characters, represented by the letter "o," numbered 10, are formed with troughs or channels 14 therein resulting from the raised and three-dimensional construction from sheet material. They are thus hollow and lightweight, and are open at their back or base 7. This construction imparts stretchability or extensibility to the characters, so that they can be stretched somewhat in their longitudinal direction, to assist in mounting the characters on the signboard.

The characters may generally be mounted by simply placing them on the outer surface 6 of the signboard with the opposed flanges 12 of the characters placed adjacent the appropriate recessed channels 4, which are D and G in the illustration for the letter "o." The characters are then pressed against the surface of the signboard, so that the flanges 12 spread and slide onto the respective channels, engaging the recessed sides 8. In some cases, it may be preferable to first insert one flange 12, then stretch the character slightly by pulling the other end, and insert the opposite flange 12 in its channel. In order to permit the characters and the flanges 12 to be pressed on in this manner, without buckling the flanges, and also to retain them on the signboard, the angle θ (Figure 4) between the flanges and the bases of the characters is preferably between 40° and 60° , and it is 50° in the illustration. The inclined sides 8 of the channels 4 preferably make the same angle α with the plane of the signboard surface 6, as illustrated. However, the angle α could be less. If it is greater, the characters are more likely to come off the signboard when not intended.

The channels A through H having inclined sides constitute a complete set for mounting all of the letters of the alphabet. Channels A and G are for the lower case letters b, d, f, h, k and l. Channels B and C are for dots. Channels B and G are for the letter t. Channels D and F are for letters of the size of the letter o. Channels E and F are for dashes. Channels D and H are for the letters g, j, p, q and y. The form of the invention illustrated is especially adapted for mounting lower case letters. However, upper case letters may be mounted as well. Additional channels 4 having recessed sides may be provided for various arrangements and types of characters. Also, the set of recessed channels 4 represented by A through H can be repeated above and below, to furnish a plurality of lines. In this manner, the sign is especially useful for departmental identification in department stores and the like, carrying such identification as "hardware," "games-toys," and "radio-television." Numerals may also be mounted on the board, and other characters might be provided such as illustrations of the items in that department or other pictorial characters.

An indentation 15 is made on the outer surface of each of the strip portions 3 under which a recessed channel side 8 extends, the indentation being adjacent the recessed side. This is for the purpose of determining immediately the location of the recessed channels, for rapid and correct mounting of the characters. Eight of the indentations are thus provided adjacent the extremities of the strip portions. Other construction, marking or devices may be employed for indicating the location of the recessed channels, but the indentations are preferred as not being apparent from a distance and thus not affecting the appearance of the sign.

The characters mounted on the signboard 2, such as the "o" 10 and the dash 11, are of stiff yet flexible resilient thermoplastic organic resinous sheet material formed into raised or three-dimensional hollow characters. The resinous material is moldable or may be formed into self-supporting characters, which are relatively rigid and remain true to shape and size. Inasmuch as the flanges 12 are subjected to considerable bending or flexing, the material must be resistant to bending fatigue. For this purpose, the resinous material is preferably a synthetic addition polymer of the unsymmetrically substituted ethylene class, comprising resins obtained by the polymerization or copolymerization of monomers containing a

group, such as vinyl halides, vinyl esters, styrene and acrylics. Of the class, those polymers are employed which can be formed and will hold a shape. Consequently, polystyrene and vinyl polymers are preferred. On the other hand, experience has been that saran, a copolymer of vinylidene chloride and vinyl chloride is not satisfactorily formed by vacuum forming methods. The preferred polymer is polystyrene, preferably high impact polystyrene. The polystyrene forms well and possesses the requisite physical properties. It is also economical and readily provided in a variety of colors.

Another preferred polymer is a copolymer of vinyl chloride and vinyl acetate, preferably containing 85% or greater by weight of vinyl chloride and the balance vinyl acetate. Other resinous materials which have the requisite physical characteristics may be employed, such as cellulose acetate butyrate and cellulose acetate. However, these modified natural resinous materials are not so desirable. They are more susceptible to atmospheric influences, tending to absorb moisture and expand and contract. Cellophane is not satisfactorily formable and is therefore not employed. Celluloid is very inflammable and undesirable for making the letters, as by vacuum forming, and in use on a sign.

It is a feature of the invention that the sign 1 composed of the signboard 2 and the characters presents a pleasing appearance, attracts attention, and is visible and readable from various angles and at considerable distances. This is in large part attributable to the provision of three-dimensional characters, that is, which have three major dimensions, each preferably greater than about $\frac{1}{4}$ -inch. The signs thus have depth and furnish true perspective. In this manner, the signs are considerably more advantageous than those previously employed wherein the characters were substantially two-dimensional, i. e., the characters were constructed of flat sheet material in two preferred dimensions and having only the thickness of the sheet.

The signboard 2 is constructed of one piece of sheet material which may be the same resinous material as employed for the characters. The physical requirements are, however, somewhat less, since there is no flexing or stretching. In fact, the signboard is preferably rigid and unyielding, furnishing a firm base and preserving the spacing and alignment of the strip portions 3 and the channel portions 4, and the angle α of the recessed sides 8. For this purpose, the sheet material forming the signboard 2 may have substantial thickness, e.g., 0.04 inch.

The thickness of the sheet material forming the characters may be 0.04 inch, before forming. After being formed, the sheet is thinner especially in the side walls 10a of the characters, which imparts greater flexibility, while the flanges 12 retain about the original thickness of the sheet. The outer wall, face or top 10b of the characters which have a flat face also retains about the original sheet thickness, imparting rigidity. The material may be selected to give the preferred characteristics in the signboard and in the characters. The signboard also is preferably formed of polystyrene, and another preferred material is vinyl chloride-vinyl acetate resin, as in the characters.

Both the signboard 2 and the characters are preferably vacuum-formed out of a single sheet of resinous material, by known methods which involve the application of heat and vacuum, followed by cooling. The unitary characters, including the flanges 12, are thus molded in one operation, and the individual characters are cut or separated from the surrounding sheet material. The flanges 12 are preferably provided at opposite sides or ends of the characters, as illustrated at 13 in the drawings. The flanges are then turned towards each other, preferably by heating and softening their junctions with the sides 13 of the characters, and then bending the flanges and cooling. One pair of flanges may be sufficient, or additional flanges may be included on some of the characters. Thus, on the letter "y," one flange is provided at the bottom of the letter and one flange is provided at the top of each of the arms of the "y."

With the new construction, there is no need for sliding letters onto the signboard from the end of the board, but they may be pressed directly into position from the front. At the same time, the letters will slide along the board, to adjust their location and spacing.

The invention thus provides a very advantageous sign. It is lightweight and very attractive, preserving the decor of an establishment. The sign is economical, portable in nature, may be mounted in any desired location, and may readily be moved from place to place. The sign is versatile and may be used for identification purposes and for displaying letters, numerals and illustrations. The sign may be read easily from substantial distances and various positions. The plastic material is colored as desired, either providing the color in the initial sheet material or coloring the surface after forming the articles. The economical nature of the characters renders it possible for an establishment to use a great variety of char-

acters, either keeping a large supply or discarding them as preferred, so that signs and displays may be moved and changed frequently.

The invention is hereby claimed as follows:

- 5 1. A lightweight changeable sign which comprises a thermoplastic organic resinous sheet having a plurality of spaced parallel elongated strip portions formed therein and comprising the surface of said sheet, a corresponding plurality of spaced depending parallel elongated channel portions formed in said sheet and alternating with said strip portions, different said channel portions each having a side recessed towards the other, and three-dimensional flexible resilient thermoplastic organic resinous characters of sheet material mountable on said sheet surface, said characters including integral flanges depending from opposite sides thereof and bent towards each other for snap-on engagement in said channel portions having a recessed side.
- 10 2. A lightweight changeable sign which comprises a rigid thermoplastic organic resinous sheet having a plurality of relatively wide spaced parallel elongated strip portions of equal width formed therein and comprising the surface of said sheet, a corresponding plurality of relatively narrow spaced depending parallel elongated channel portions formed in said sheet and alternating with said strip portions, different said channel portions each having a side recessed towards the other, said sheet bearing indicia on the locations of said recessed sides, and extensible three-dimensional flexible resilient thermoplastic organic resinous characters of sheet material mountable on said sheet surface, said characters including integral flanges depending from opposite sides thereof and bent towards each other at angles of 40° to 60° with the base of the characters for snap-on engagement in said channel portions having a recessed side.
- 15 3. A lightweight changeable sign which comprises a rigid thermoplastic organic resinous sheet having a plurality of relatively wide spaced parallel elongated strip portions of equal width formed therein and comprising the surface of said sheet, a corresponding plurality of relatively narrow spaced depending parallel elongated channel portions formed in said sheet and alternating with said strip portions, different said channel portions each having a side recessed towards the other, said sheet bearing indicia on the locations of said recessed sides, and extensible three-dimensional flexible resilient thermoplastic organic resinous characters of sheet material mountable on said sheet surface, said characters including integral flanges depending from opposite sides thereof and bent towards each other at angles of 40° to 60° with the base of the characters for snap-on engagement in said channel portions having a recessed side.
- 20 4. A lightweight changeable sign which comprises a rigid thermoplastic organic resinous sheet having a plurality of relatively wide spaced parallel elongated strip portions of equal width formed therein and comprising the surface of said sheet, a corresponding plurality of relatively narrow spaced depending parallel elongated channel portions formed in said sheet and alternating with said strip portions, different said channel portions each having a side recessed towards the other, said sheet bearing indicia on the locations of said recessed sides, and extensible three-dimensional flexible resilient thermoplastic organic resinous characters of sheet material mountable on said sheet surface, said characters including integral flanges depending from opposite sides thereof and bent towards each other at angles of 40° to 60° with the base of the characters for snap-on engagement in said channel portions having a recessed side.
- 25 5. A lightweight changeable sign which comprises a rigid thermoplastic organic resinous sheet having a plurality of relatively wide spaced parallel elongated strip portions of equal width formed therein and comprising the surface of said sheet, a corresponding plurality of relatively narrow spaced depending parallel elongated channel portions formed in said sheet and alternating with said strip portions, different said channel portions each having a side recessed towards the other, said sheet bearing indicia on the locations of said recessed sides, and extensible three-dimensional flexible resilient thermoplastic organic resinous characters of sheet material mountable on said sheet surface, said characters including integral flanges depending from opposite sides thereof and bent towards each other at angles of 40° to 60° with the base of the characters for snap-on engagement in said channel portions having a recessed side.
- 30 6. A lightweight changeable sign which comprises a rigid thermoplastic organic resinous sheet having a plurality of relatively wide spaced parallel elongated strip portions of equal width formed therein and comprising the surface of said sheet, a corresponding plurality of relatively narrow spaced depending parallel elongated channel portions formed in said sheet and alternating with said strip portions, different said channel portions each having a side recessed towards the other, said sheet bearing indicia on the locations of said recessed sides, and extensible three-dimensional flexible resilient thermoplastic organic resinous characters of sheet material mountable on said sheet surface, said characters including integral flanges depending from opposite sides thereof and bent towards each other at angles of 40° to 60° with the base of the characters for snap-on engagement in said channel portions having a recessed side.
- 35 7. A lightweight changeable sign which comprises a rigid thermoplastic organic resinous sheet having a plurality of relatively wide spaced parallel elongated strip portions of equal width formed therein and comprising the surface of said sheet, a corresponding plurality of relatively narrow spaced depending parallel elongated channel portions formed in said sheet and alternating with said strip portions, different said channel portions each having a side recessed towards the other, said sheet bearing indicia on the locations of said recessed sides, and extensible three-dimensional flexible resilient thermoplastic organic resinous characters of sheet material mountable on said sheet surface, said characters including integral flanges depending from opposite sides thereof and bent towards each other at angles of 40° to 60° with the base of the characters for snap-on engagement in said channel portions having a recessed side.
